UNITED STATES PATENT OFFICE.

RICHARD WALWORTH, OF WALTHAM, MASSACHUSETTS.

BOBBIN-STRIPPER.

1,080,942.

Specification of Letters Patent.

Patented Dec. 9, 1913.

Application filed November 20, 1912. Serial No. 732,435.

To all whom it may concern:

Be it known that I, RICHARD WALWORTH, a citizen of the United States, residing at Waltham, in the county of Middlesex, State 5 of Massachusetts, have invented a certain new and useful Improvement in Bobbin-Strippers, of which the following is a specification, reference being had therein to the accompanying drawings.

10 My present invention is an improvement upon that of my prior application for United States Letters Patent filed December 8, 1908, Serial No. 466,553. Like that of my prior application, it is designed for stripping from spools and bobbins employed in the spinning and weaving processes the small quantities of roving or yarn remaining thereon when they are replaced by full spools or bobbins.

20 My present invention is characterized by the employment of an endless flexible traveling surface having a working run of any approved length. The said working run preferably travels in a downwardly inclined 25 direction, and has combined therewith bobbin-rests, the latter being preferably in the form of rollers, and being revolved by contact with the said traveling surface. The said bobbin-rests extend transversely across 30 the said surface, discharge openings for empty spools or bobbins being provided laterally of the traveling surface adjacent each bobbin-rest.

An embodiment of the invention is 35 shown in the drawings, in which latter,—

Figure 1 is a plan view of the said embodiment. Fig. 2 is a view in vertical section in the plane of line 2, 2, of Fig. 1. Fig. 3 is a detail view.

40 Having reference to the drawings,—a suitable frame-work 1 has journaled thereon rolls 2 and 3, around which an endless apron 4 extends. The said apron is caused to travel by means of any suitable driving 45 connections, which latter are represented by fast and loose band-pulleys 5, 5^a, on the shaft of the roll 2. The roll 3 is lower than roll 2, so that the upper run of the apron, which is the working run, extends at a downward 50 inclination from the roll 2 to the roll 3. Bobbin-rests are shown in the form of rolls 8, 8, and 9, 9, extending transversely across the working run of the endless apron, and

making contact with the surface thereof. The journals of these rolls occupy notches 55 10^a in metal plates 10, 10, that are attached to the machine framework by bolts 10^b, 10^b, passing through slots 10^c, 10^c, in such plates, but other forms of bearings or stops for the said journals, to determine the positions occupied by the bobbin-rests, may be employed in practice according to preference. Certain of the bobbin-rests, namely those 60 designated 8, 8, extend across the working run of the traveling surface inclined at an 65 angle in one direction to the length of the latter, and those designated 9, 9, extend across the said run inclined at an angle in the opposite direction. The drawings show bobbins 11, 11, adjacent the respective bobbin- 70 rests. A spool or bobbin laid upon the traveling surface at the upper side of a bobbin-rest will be kept by the traveling movement of the said surface against the said rest, and at the same time will be rotated upon its individual axis. Meanwhile, the free end of a roving or yarn *a* on the 75 spool or bobbin, becoming adherent to the traveling surface and carried forward thereby, will be unwound from the spool or 80 bobbin. Engagement of the roving or yarn with the traveling surface may be depended upon, if such surface is of suitable character, but I prefer to effect the unwinding through the coöperation of the rolls 8, 85 8, and 9, 9, with the traveling surface, the roll against which a given spool or bobbin rests acting to hold the roving or yarn leading from said spool or bobbin pressed 90 against the traveling surface, and coöperating with the said surface as a feed-roll to nip and assist in feeding the roving or yarn so as to draw it from the spool or bobbin. The bobbin-rests are set so as to cause the 95 spools or bobbins to occupy positions in which the axis of each individual spool or bobbin stands at a forward inclination with respect to the traveling surface. By reason of the inclined position taken by the spool-axis or bobbin-axis while the spool or 100 bobbin is in contact with a bobbin-rest, the rotation of the spool or bobbin by its contact with the traveling surface causes an endwise movement of the said spool or bobbin transversely of the traveling surface to 105 take place, until the spool or bobbin dis-

charges from the said traveling surface through one of the discharge openings 13, 13. A bobbin in contact with a rest travels endwise with the forwardly-inclined end 5 of its axis foremost. In the drawings, the inclinations of rests 8 and 9 are such that a bobbin in contact with a rest 8 travels small end first until it discharges at the left-hand side of the machine, while a bobbin in 10 contact with a bobbin-rest 9 travels head-end first until it discharges at the right-hand side of the machine. By disposing the bobbin-rests in an alternating succession comprising one or more inclined at one 15 angle across the endless traveling surface, and one or more inclined at an opposite angle, the bobbins at such rests may be caused to discharge at opposite sides of the machine in the same alternating succession. 20 If desired, for the purpose of varying the rate of travel of the bobbins endwise, the inclination of the rests may be varied by adjusting the bearing-plates 10, 10, lengthwise of the travel of the apron. This same adjustment is utilized in setting the rests to 25 suit either bobbins having one end larger in diameter than the other as in the drawings, or both ends of the same diameter. In any case, the angles of the respective rests with 30 reference to the endless traveling surface will be proportioned so as to give the axis of a bobbin the required inclination respecting the direction of travel of the traveling surface to insure endwise travel of the bobbin 35 in the desired direction and further to insure complete cleaning or stripping of the bobbins before they are discharged; and such angles will also be proportioned to the 40 capacity of the attendant or attendants who feed the machine with bobbins to be stripped. The machine shown, it having four bobbin rests, is intended to be served by four boys or other attendants, two at each end of the machine, standing side by side, or they 45 might stand alongside the machine, this depending on the arrangements made for taking care of the stripped bobbins as they are discharged from the machine. The machine may be extended in length as much as may 50 be required and any desired number of attendants may be thereby accommodated. Hence the machine may be given any required capacity.

The rovings or yarns *a*, *a*, are stripped 55 from the surface of the apron 4 by any convenient means, as for instance a brush 15, Fig. 2. Stripper brushes 16, 16, are provided in connection with the respective bobbin-rests 8, 9, to prevent the rovings or yarns 60 from winding thereon. These brushes 16, 16, rest upon the bobbin-rests, and may be held in working position with relation thereto by having the ends of their backs notched,

as at 16^a, 16^a, to receive projections 10^d, 10^d, rising from the bearing-plates 10, 10. 65

What is claimed as the invention is:—

1. A bobbin-stripping machine comprising, essentially, an endless flexible traveling surface having a working run extended in a direction to receive and support spools 70 or bobbins to be stripped, and bobbin-rests extending transversely across the said working run and arranged to maintain a spool-axis or bobbin-axis inclined with reference to the direction of travel of the said working 75 run, said endless traveling surface acting to unwind rovings or yarns from said spools or bobbins and feed the latter lengthwise.

2. A bobbin-stripping machine comprising, essentially, an endless traveling apron 80 having a working run extended at an inclination and adapted to receive and support spools or bobbins to be stripped, and bobbin-rests extending transversely across the said working run, and adapted to maintain the 85 axis of a spool or bobbin at an inclination to the direction of movement of said run, whereby endwise travel and a discharge of the spools or bobbins are produced.

3. A bobbin-stripping machine comprising, essentially, an endless traveling apron having a working run adapted to receive and support spools or bobbins to be stripped, bobbin-rests extending transversely across said working run, and means to adjust said 95 bobbin-rests angularly with relation to the direction of travel of said run, said apron acting to unwind rovings or yarns from said spools or bobbins and feed the latter lengthwise. 100

4. A bobbin-stripping machine comprising, essentially, an endless flexible traveling surface having a working run extended in a direction to receive and support spools or bobbins to be stripped, and bobbin rests constituted by rolls extending transversely across the said working run, resting thereon, and arranged to maintain a bobbin-axis inclined with reference to the direction of travel of the said working run, said endless 110 traveling surface acting to unwind rovings or yarns from said spools or bobbins and feed the latter lengthwise.

5. A bobbin-stripping machine comprising, essentially, an endless traveling apron 115 having a working run extended at an inclination and adapted to receive and support spools or bobbins to be stripped, and bobbin-rests constituted by rolls extending transversely across the said working run, resting 120 thereon, and adapted to maintain the axis of a spool or bobbin at an inclination to the direction of movement of said run, whereby endwise travel and a discharge of the spools or bobbins are produced. 125

6. A bobbin-stripping machine comprising

ing, essentially, an endless traveling apron having a working run adapted to receive and support spools or bobbins to be stripped, bobbin-rests constituted by rolls extending 5 transversely across said working run and resting thereon, and means to adjust said bobbin-rests angularly with relation to the direction of travel of said run, said apron acting to unwind rovings or yarns from said

spools or bobbins and feed the latter lengthwise.

In testimony whereof I affix my signature in presence of two witnesses.

RICHARD WALWORTH.
